CLAIM

The ornamental design for a clamp-on holder for LED lamp, as shown and described.

DESCRIPTION

FIG. 1 is a perspective view of a clamp-on holder for LED lamp showing my new design;

FIG. 2 is a front elevational view thereof;

FIG. 3 is a rear elevational view thereof;

FIG. 4 is a top plan view thereof;

FIG. 5 is a bottom end view thereof;

FIG. 6 is a right side elevational view thereof;

FIG. 7 is a sectional view along line 7—7 of FIG. 2;

FIG. 8 is a sectional view along line 8—8 of FIG. 2;

FIG. 9 is a sectional view along line 9—9 of FIG. 2;

FIG. 10 is a perspective view showing the use as a clamp-on holder for LED lamp fitting to the frame member. The broken lines are for illustrative purpose only and form no part of the claimed design; and,

FIG. 11 is a rear perspective view of a clamp-on holder for LED lamp.
